UNITED STATES PATENT OFFICE.

BENNO VOM EIGEN, OF NEWARK, NEW JERSEY, ASSIGNOR TO AUGUST GOERTZ & CO., A CORPORATION OF NEW JERSEY.

MATCH-BOX.

1,108,429.

Specification of Letters Patent.

Patented Aug. 25, 1914.

Application filed November 4, 1913. Serial No. 799,655.

To all whom it may concern:

Be it known that I, BENNO VOM EIGEN, a citizen of the United States, residing at Newark, in the county of Essex and State of New Jersey, have invented certain new and useful Improvements in Match-Boxes; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention has reference, generally, to improvements in the art pertaining to the construction of match-boxes, and, the invention relates, more particularly, to a novel construction of match-box, with a view of simplifying the general construction of the match-box, and, at the same time, facilitating the assembling of the various parts of the match-box.

The invention, therefore, has for its general purpose to provide a match-box construction with the above stated objects in view, and to generally simplify and cheapen the cost of manufacture of the same.

Other objects of the invention not at this time more particularly enumerated will be clearly understood from the following detailed description of the said invention.

With the various objects of the present invention in view, the invention consists, primarily, in the novel match-box hereinafter set forth; and, the invention consists, furthermore, in the novel arrangements and combinations of the various devices and parts, as well as in the details of the construction of the same, all of which will be more fully described in the following specification, and then finally embodied in the clauses of the claim which are appended to and which form an essential part of this specification.

The invention is clearly illustrated in the accompanying drawings, in which:

Figure 1 is a side elevation of a match-box made according to and embodying the principles of the present invention; Fig. 2 is a top-edge view of the same; and Fig. 3 is a longitudinal vertical section of the match-box. Fig. 4 is a transverse vertical section of the match-box, said section being taken on line 4-4 in said Fig. 3, looking in

the direction of the arrow *x*; and Fig. 5 is a horizontal section taken on line 5-5 in said Fig. 3, looking in the direction of the arrow *y*. Fig. 6 is a collective perspective view of the various parts of the match-box, showing said parts in their disassembled relations, prior to being put together to produce the complete match-box.

Similar characters of reference are employed in the said above described views, to indicate corresponding parts.

Referring now to the said drawings, the reference-character 1 indicates the main shell or casing of the match-box, the same being made of sheet-metal suitably ornamented, and in the form of a book, comprising the two side-plates 2 and 3, joined together by a back-edge member 4. At the edges, where the respective side-plates 2 and 3 are connected with the back-edge member 4, the metal is suitably curved, as at 5 and 6, see Figs. 2, 5 and 6 of the drawings, so as to provide within the said main shell or casing a pair of channels or guiding retaining portions 7 and 8 for the purposes to be presently set forth. Referring to Fig. 6 of the drawings, for the sake of clearness, the member 4 will hereinafter be called the back, and the open spaces 9, 10 and 11 located between the respective edge-portions of the side-plates 2 and 3, will hereinafter, respectively, be called the top, the front, and the bottom. Suitably located in the said front, and near the marginal edges of the said side-plates 2 and 3, is a closing plate-like member, as 12, which is formed with a pair of marginal flanges 13 from which extend suitably disposed lugs or projections, as 14. Extending upwardly and outwardly from the upper end-portion of said plate-like member 12 is a hook-shaped holding or retaining member 15, and projecting at right angles from the lower end-portion of said plate-like member 12 is another plate-like member, as 16, which is also formed with marginal flanges, as 17, and an arrangement of cut-away parts 18 and 19, forming lug-receiving recesses for the purposes herein-after more fully stated.

Having properly arranged the said plate-like member 12 in the front, and the plate-like member 16 in the bottom, between the two side-plates 2 and 3, these parts are permanently secured in place by means of the application of solder 20 between the said lugs or projections 14 and the flanges 17,

and the inner face-portions of the said side-members or plates 2 and 3, substantially as indicated in Figs. 3, 4 and 5 of the drawings. From an inspection of said Figs. 3 and 5 it will also be seen, that the said plate-like member 16, when inserted in place, is located slightly away from the marginal edges of the bottom between said side-plates 2 and 3, and, furthermore, that the said member 16 is shorter than the widths of said side-plates 2 and 3, so that a space is left between the end-edge 21 of said member 16 and the lower inner surface-portion of the back formed by the back-edge member 4. Slipped into the channels or guiding retaining portions 7 and 8, so as to be held and disposed upon the inner face of the said back, is another plate-like member 22, said member being provided at its upper end with a pair of perforated marginal pintle-receiving lugs or ears 23, and also with a pair of marginal guide-lugs 24, and another pair of spring-retaining lugs 25. Secured upon the face-portion 26 of said plate-like member 22, by means of said retaining lugs 25, is a spring-plate 27, movable at its upper end-portion between the said guide-lugs 24, said spring-plate being also formed upon said upper end-portion with an upwardly extending angular tongue-like member 28. Rotatably connected with and mounted between the said pintle-receiving lugs or ears 23 is a pintle 29 upon which is suitably mounted the angular portion 31 of a hinge-plate 30, said plate 30 having a part 32 extending downwardly and upwardly, and then slightly outwardly, as at 33, whereby a suitable hinge-lug is provided which is in slideable engagement with the angular tongue-like member 28 of the spring-plate 27, and the action of which is to maintain the said hinge-plate 30, forming the lid of the match-box, in either its closed or opened relation, as will be clearly understood. Upon its lower end-portion, the said plate-like member 22 is formed with an inwardly projecting right-angled portion 34, which extends into the bottom between the said side-plates 2 and 3, in the same plane with the plane of the previously-mentioned plate-like member 16, as clearly shown in Fig. 3 of the drawings. The said right-angled portion 34 is also made with marginal cut-away portions, as 35. As soon as the various parts hereinbefore described have been brought into proper relative positions between the two side-plates 2 and 3, a plate-like member 36 is placed in the bottom between said side-plates, so as to be mounted upon the horizontally aligned plate-like member 16 and the right-angled portion 34, the said plate-like member 36 being formed at its one end with marginal extensions 37 which correspond to the inner contour of and are fitted in the pre-

viously-mentioned channels or guiding retaining portions 7 and 8, said plate-like member 36 being also provided with suitably disposed and upwardly projecting fastening lugs 38. The said lugs 38 are inserted through the various lug-receiving recesses 18 and 19 of the plate-like member 16, and through the marginal cut-away portions 35 of the right-angled portion 34, and then bent over upon the said parts, as shown in said Figs. 3, 4 and 5 of the drawings, whereby the match-box construction is completed and the assembled parts, between the said side-plates 2 and 3, are positively held in place against displacement. The said plate-like member 36 is also made with a hook-shaped end-portion 39, which, with the hook-shaped retaining member 15 of the plate-like member 12, is brought down over the stepped ends 41 of a scratching medium 40 arranged upon a backing 42, and is thus suitably disposed in the front of the completed match-box, as clearly illustrated in Figs. 3 and 5 of the drawings.

I am aware, that some changes may be made in the general arrangements and combinations of the several devices and parts, as well as in the details of the construction of the said parts, without departing from the scope of the present invention as set forth in the foregoing specification and as illustrated in the accompanying drawings. Hence, I do not limit myself to the exact details of the general arrangements and combinations of the devices and parts as described in the said specification, nor do I confine myself to the exact details of the construction of the said parts as illustrated in the accompanying drawings.

I claim:—

1. A match-box comprising a pair of side-plates and a connecting back-edge member, said side-plates and back-edge member being formed at their connected parts with guiding retaining portions, plate-like closing members secured in the front and bottom of the match-box between the marginal edge-portions of said side-plates, and another plate-like member slidably mounted in said guiding retaining portions, said last-mentioned plate-like member being provided with a hinged lid and a spring-member in engagement with a portion of said lid.
2. A match-box comprising a pair of side-plates and a connecting back-edge member, said side-plates and back-edge member being formed at their connected parts with guiding retaining portions, plate-like closing members secured in the front and bottom of the match box between the marginal edge-portions of said side-plates, another plate-like member slidably mounted in said guiding retaining portions, said last-mentioned plate-like member being provided with a hinged lid and a spring-member in engage- 130

ment with a portion of said lid, and a plate-like member in the bottom of the match-box provided with means in engagement with a portion of the plate-like member in the back of the match-box to secure said last-mentioned plate-like member in its fixed position in said guiding retaining portions.

3. A match-box comprising a pair of side-plates and a connecting back-edge member, 10 said side-plates and back-edge member being formed at their connected parts with guiding retaining portions, plate-like closing members secured in the front and bottom of the match-box between the marginal edge-15 portions of said side-plates, another plate-like member slidably mounted in said guiding retaining portions, said last-mentioned plate-like member being provided with a hinged lid and a spring-member in engagement-20 with a portion of said lid, and a forwardly projecting lower end-portion also connected with said last-mentioned plate-like member, and a plate-like member in the bottom of the match-box provided with-25 means in engagement with a portion of said forwardly projecting end-portion of the plate-like member in the back of the match-box to secure said last-mentioned plate-like member in its fixed position in said guiding-30 retaining portions.

4. A match-box comprising a pair of side-plates and a connecting back-edge member, said side-plates and back-edge member being provided at their connected parts with guiding retaining portions, plate-like closing members secured in the front and bottom of the match-box between the marginal edge-35 portions of said side-plates, another plate-like member slidably mounted in said guiding retaining portions, said last-mentioned plate-like member being provided with a hinged lid and a spring-member in engagement-40 with a portion of said lid, and a forwardly projecting lower end-portion also connected with said last-mentioned plate-like member, said forwardly projecting lower end-portion being formed with marginal lug-receiving cut-away recesses, and a plate-like member in the bottom of the-45 match-box provided with marginal retaining lugs inserted in said cut-away recesses and bent over said forwardly projecting lower end-portion of the plate-like member in the back of the match-box to secure said last-mentioned plate-like member in its fixed position in said guiding retaining portions.

5. A match-box comprising a pair of side-60 plates and a connecting back-edge member, a plate-like member in the front and part of the bottom of the match-box, said plate-like member being provided with marginal flanges and lugs arranged between the inner face-portions of said side-plates, means for permanently securing said lugs to said side-

plates, and a plate-like portion extending at right angles from the lower end of said plate-like member, said plate-like portion being arranged in the bottom of the match-box between said side-plates, another plate-like member arranged in the back of the match-box, said last-mentioned plate-like member being provided with a hinged lid and a spring-member in engagement with said lid, and a plate-like member in the bottom of the match-box provided with means in engagement with the right-angled plate-like portion which extends from the plate-like member in the front of the match-box and also with the plate-like member in the back of the match-box.

6. A match-box comprising a pair of side-plates and a connecting back-edge member, a plate-like member in the front and part of the bottom of the match-box, said plate-like member being provided with marginal flanges and lugs arranged between the inner face-portions of said side-plates, means for permanently securing said lugs to said side-plates, and a plate-like portion extending at right angles from the lower end of said plate-like member, said plate-like portion being arranged in the bottom of the match-box between said side-plates, another plate-like member arranged in the back of the match-box, said last-mentioned plate-like member being provided with a hinged lid and a spring-member in engagement with said lid, and a forwardly projecting lower end-portion also connected with said last-mentioned plate-like member, and a plate-like member in the bottom of the match-box provided with means in engagement with the right-angled plate-like portion which extends from the plate-like member in the front of the match-box and also with said forwardly projecting lower end-portion of the plate-like member in the back of the match-box.

7. A match-box comprising a pair of side-plates and a connecting back-edge member, a plate-like member in the front and part of the bottom of the match-box, said plate-like member being provided with marginal flanges and lugs arranged between the inner face-portions of said side-plates, means for permanently securing said side-lugs to said side-plates, and a plate-like portion extending at right angles from the lower end of said plate-like member, said plate-like portion being arranged in the bottom of the match-box between said side-plates, said plate-like portion being provided with marginal lug-receiving recesses, another plate-like member arranged in the back of the match-box, said last-mentioned plate-like member being provided with a hinged lid and a spring-member in engagement with said lid, and a forwardly projecting lower end-portion also connected with said last-

- mentioned plate-like member, said forwardly projecting lower end-portion being also provided with marginal lug-receiving recesses, a plate-like member in the bottom 5 of the match-box, and marginal retaining lugs extending upwardly from said plate-like member in the bottom of the match-box, said marginal retaining lugs being inserted in said marginal lug-receiving recesses and 10 bent over said plate-like portion of the plate-like member in the front of the match-box and over said forwardly projecting lower end-portion of the plate-like member in the back of the match-box.
- 15 8. In a match-box, in combination with the box-shell or casing, provided at its back with a pair of guiding retaining portions, of a spring-controlled hinge-lid bearing plate-like member slidably disposed in said guiding retaining portions.
- 19 9. In a match-box, in combination with the box-shell, or casing, provided at its back with a pair of guiding retaining portions, of a spring-controlled hinge-lid bearing plate- 25 like member slidably disposed in said guiding retaining portions, and means connected

with said shell or casing for retaining said plate-like member in its fixed position in said guiding retaining portions.

10. In a match-box, in combination with 30 a box-shell or casing comprising a pair of side-plates, a plate-like member secured between said side-plates at the front of the match-box, said plate-like member being provided at one end with a hook-shaped member, a second plate-like member also secured between said side-plates at the bottom of the match-box, said last-mentioned plate-like member being also provided with a hook-shaped member, and a match-scratching element mounted upon said first-mentioned plate-like member and secured in place by the hook-shaped members of said two plate-like members.

In testimony, that I claim the invention 45 set forth above I have hereunto set my hand this 28th day of October, 1913.

BENNO VOM EIGEN.
